UNITED STATES PATENT OFFICE.

JOHN BLACK, OF NEW YORK, N. Y., ASSIGNOR OF ONE-HALF TO JEFFERSON T. RAPLEE, OF SAME PLACE.

GRAIN-DRIER.

SPECIFICATION forming part of Letters Patent No. 389,048, dated September 4, 1883.

Application filed October 5, 1887. Serial No. 251,539. (No model.)

To all whom it may concern:

Be it known that I, JOHN BLACK, a citizen of the United States, and a resident of New York, in the county of New York and State of New York, have invented certain new and useful Improvements in Grain-Driers; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a transverse section of my improved grain-drier. Fig. 2 is a vertical longitudinal section of same. Fig. 3 is a detail section of chain, showing scrapers *m*. Fig. 4 is a plan or top view of chain.

The invention relates to improvements in grain-driers, being especially adapted to drying barley or brewers' grain for the use of brewers; and it consists in the construction and novel combination of parts hereinafter described, illustrated in the drawings, and pointed out in the appended claim.

Referring to the drawings by letter, *A* designates the casing of the machine, made preferably of boiler-iron, and triangular in vertical longitudinal section, the end surfaces converging upward at equal angles to the horizontal top *a*, to which is attached near one end the flue *B*, adapted to be attached by tubing to a suitable exhaust-fan, and near the opposite end the feed-hopper *b* for the grain.

C is a delivery-chute opening from the bottom plate of the machine from a point below the discharge end of the lowest drier or grain-platform. The exhaust-flue *B* is provided with a suitable valve or damper, *b'*, to cut off or lessen the current from the casing when necessary.

D D are a number of equal horizontal steam-chambers extending from near the top to near the bottom of the casing, and nearly from side to side thereof, each of said chambers extending outward at both ends to equal distances beyond the chamber next above, for purposes hereinafter explained. The upper plates, *d*, of the steam-chambers form the grain-platform, and are provided on their side edges with the

vertical flanges *d'* to retain the grain upon them. The steam-chambers are of boiler-iron thick enough to stand a pressure of about one hundred and twenty-five pounds to the square inch, and extend to equal distances from the ends of the casing, so that the only direct air-drafts are up between the casing and the ends of the steam-chambers.

E is a vertical steam-pipe, receiving steam from any proper source of supply, and provided with branch pipes *F*, that convey steam to each of the steam-chambers *D*. These branch pipes *F* are provided with cut-off valves *f*, so that the flow of steam to each chamber can be graduated or cut off entirely when necessary.

G is a vertical exhaust-pipe, preferably on the other side and near the opposite end of the casing from the steam-pipe *E*, and *H H* are branch pipes connecting the steam-chambers and exhaust-pipe, and provided with the cut-off valves *h*. By means of the valves *f* and *h* the flow of steam can be regulated through each chamber separately, as the necessities of the operation require, or the steam may be accumulated in each or any chamber until the pressure therein reaches the desired point.

I I' are two long pulleys on a shaft, *i*, receiving motion from any suitable motor, and journaled in bearings on suitable supports.

J J' designate a number of sets of pulleys on shafts *j j'*, situated between the opposite ends of each steam-chamber and the adjacent end of the casing, the pulleys *J* being on the opposite side of the casing from the pulleys *J'*. The shafts *j j'* are journaled in bearings in the sides of the casing, and the pulleys *J J'* are secured on their respective shafts outside of the casing and at different distances therefrom, so that the belts *K K'*, by means of which the said pulleys receive motion from the pulley *I*, will not interfere with each other.

The belts *K* extend from the pulley *I* to the pulleys *J* on the shafts *j*, and crossed belts *K'* from the pulley *I'* rotate the pulleys *J'* on the shafts *j'* in a direction opposite to that of the pulleys *J*.

L L are sprocket or chain wheels on the shafts *j j'* within the casing, and *M M* are chains connecting each pair of sprocket-wheels and moving over the grain-platforms *d*. The sprocket wheels and chains are arranged in

equidistant pairs corresponding with each steam-chamber.

It is evident from the foregoing that the chains move in opposite directions over each 5 succeeding platform, so that the grain in its descent is carried from end to end of the casing.

The chains are provided with equidistant cross-bars or scrapers *m m*, and the chains of 10 each pair move adjacent to the opposite vertical retaining-flanges *d'* of the corresponding platform *d*.

The machine is provided with the necessary bearing - supports for the shafts, the pillow-blocks, and other necessary and ordinary parts, 15 which may vary in shape, position, and number according to circumstances, and which, as they fall within the scope of ordinary workmanship, are not patentable elements, except 20 when they are necessary to a new and useful purpose.

The method of operation is as follows: The grain to be dried is poured in through the hopper and carried thence by the highest chain over 25 the highest grain-platform by the described means. At the end of the first platform it falls on the extension of the second platform and is carried by the second chain in the reverse direction, falling on the third platform, and so 30 on till it is delivered from the last platform into the discharging chute. As the grain descends it becomes drier and loses part of its moisture in the form of steam, and the said steam, being heated, ascends and converges and 35 concentrates over the highest and shortest platform the greatest amount of heat where the heat is most needed—that is, at the top of the casing, where it immediately prevents or stops the fermentation of the grain, the grain being 40 there in its coolest and most moist condition. In fact, the upward narrowing of the casing, in connection with the exhaust therefrom, causes the air and steam to pass more quickly over

each platform from below upward, and the said air and steam become more heated as they 45 ascend, because they receive successively the heat from the platforms. This action is equivalent to passing more and hotter air over the successively higher platforms during the same time. The increased length of the successive 50 platforms as they descend permits a free and direct upward escape of heated steam from the grain at the discharge end of each platform after it has passed over the latter, which steam as it rises radiates its heat to the grain on the 55 successive platforms, but carries its moisture with it, so as not to interfere with the drying of the grain.

The described action would be impossible if the casing were rectangular and not narrower 60 at the top than at the bottom, or if the successive platforms were not longer at both ends than those above, as each platform receives the grain from the platform immediately above at one end, and allows the moisture to ascend 65 in the form of steam from the other end without imparting moisture to the platforms above.

Having described my invention, I claim—

In a grain - drier, the combination, with the casing upwardly converging, the feeding- 70 hopper and exhaust-flue in the top of the casing, and the discharge-chute in the bottom thereof, of the horizontal steam-chests successively increasing in length, the lower chest extending at its ends beyond the chest or chests 75 above it, the upper plates of said chests forming grain-platforms and having the flanged sides, and the mechanism described, whereby the grain is moved in opposite directions to the discharge-chute, substantially as specified. 80

In testimony whereof I affix my signature in presence of two witnesses.

JOHN BLACK.
